SAMUEL IVERS, OF NEW BEDFORD, MASSACHUSETTS.

Letters Patent No. 83,501, dated October 27, 1868.

IMPROVEMENT IN NEEDLES.

The Schedule referred to in these Letters Patent and making part of the same.

To all persons to whom these presents may come:

Be it known that I, SAMUEL IVERS, of New Bedford, in the county of Bristol, and State of Massachusetts, have invented a new and useful Improvement in Sewing-Needles; and I do hereby declare the same to be fully described in the following specification, and represented in the accompanying drawings, of which—

Figures 1, 2; 3, 4, 5, 6, and 7, are side views of needles of common forms, provided with my invention.

Figure 8 exhibits the mode in which one of my improved needles is held in one hand and threaded by a thread, B', looped around the index-finger of the other hand of a person.

The purpose of that part of the needle to which my improvement specially refers is to enable the needle to be threaded with facility and dispatch, without requiring the thread to be passed endwise into and down through the eye of the needle; and the nature of my improvement consists in constructing the eye with a lateral opening and an elastic hook, and an inelastic head at the root of such hook, or with the same and an elastic or an inelastic abutment, arranged together in manner as represented in the accompanying drawings.

I would remark that I am aware that a needle has been constructed with a hook at one end, and a point at its opposite end, the said hook being inelastic and to catch upon the thread, so as to enable the needle, while in use, to draw it through a piece of cloth or other article. I am also aware that a "tag-needle" has been made, with a notch or mouth in its head or upper end, to lead into an eye, provided with a spring to close the eye, such being as represented in the United States patent, No. 53,638.

I am also aware of the needle represented in No. 37,996 of United States patents, and, consequently, I make no claim to the three needles herein last mentioned, as mine differs essentially from them.

In the first place, the eye or eye-part of my needle is composed of an elastic hook, and a notch below such hook, and, in continuation of the opening of the hook, the point or end of the hook being bevelled and lapped on the part or abutment below it, or extended into the notch, in the manner as shown at A, in the accompanying drawings, in which *a* denotes the eye, *b* the elastic part or spring of the hook *B*, *c* the inelastic abutment, against which the bevelled end of the part *b* bears.

It will also be observed, that at the upper end of the eye, and joined with the elastic part *b*, there is an in-

elastic head, from which the part *b* springs. This head is to be inelastic, so that when pressed against by the thimble of a seamstress, while in the act of forcing the needle into a piece of cloth or other material, it shall so resist the pressure as to prevent any inward springing of the part *b*.

In fig. 7, the part shown at *c* is intended to be elastic, as a straight spring, for the purpose of enabling a thread to be readily drawn out of the needle laterally, and between the ends of the two springs *b* *c*.

In figs. 3 and 4, the eye is exhibited as formed somewhat different from what it is in the remaining figures, in which it is shown as made quite long, with parallel sides and rounded ends.

In threading the needle, it is only necessary to stretch the thread across the tongue or spring *b*, pull the thread toward the needle, and slip the thread down on and beyond the end of the spring or tongue *b*. The tongue will be sprung back from the abutment *c*, and will allow the thread to pass into the eye.

With my needle, the loop of the thread rests against the base of the hook or top of the eye, while the needle may be in the act of drawing the thread into a piece of cloth or other material, and, consequently, there is no chance for the spring to give way, under the draught or pressure of the thread, and let the thread out of the eye.

I make no claim to the needle described in the United States patent, No. 31,153, in which, to form the eye, the needle is forked, and has its longer prong bent around against the shorter one, thus rendering the eye very weak and elastic at its upper end, and liable to spring or collapse under the pressure of a thimble.

I have improved such needle by combining with it an inelastic head, arranged as described.

I claim as my invention—

My improved needle, made substantially as described and represented; that is, with an opening leading out of one side, rather than one end of the eye, and also with an inelastic head at the upper end of the eye, and with an elastic hook, and either an elastic or inelastic abutment, constructed and arranged together, substantially in manner and so as to form the eye, as hereinbefore explained, the whole being to operate as set forth.

SAMUEL IVERS.
